(57) **CLAIM**

The ornamental design for a garment with pouch, as shown and described.

DESCRIPTION

FIG. 1 is a front perspective view of a first embodiment of a design for a garment with pouch, the pouch having an opening at the top and a closed seam at the bottom of the pouch;

FIG. 2 is a cross-sectional view thereof taken from line 2-2 in FIG. 1 from the front perspective view;

FIG. 3 is a rear perspective view thereof that illustrates the back of the garment lifted in order to show the pouch on the inside on the front of the garment;

FIG. 4 is an additional rear perspective view thereof that illustrates the back of the garment lifted in order to show the pouch on the inside on the front of the garment;

FIG. 5 is a front view thereof;

FIG. 6 is a rear view thereof;

FIG. 7 is a left-side view thereof;

FIG. 8 is a right-side view thereof;

FIG. 9 is a top view thereof; and

FIG. 10 is a bottom view thereof;

FIG. 11 is a front perspective view of a second embodiment of a design for a garment with two pouches, the pouches being open at the top of the pouch;

FIG. 12 is a cross-sectional view thereof taken from line 12-12 in FIG. 11 from the front perspective view;

FIG. 13 is a rear perspective view thereof that illustrates the back of the garment lifted in order to show the pouch on the inside on the front of the garment;

FIG. 14 is an additional rear perspective view thereof that illustrates the back of the garment lifted in order to show the pouch on the inside on the front of the garment;

(Continued)

FIG. 15 is a front perspective view of a third embodiment of a design for a garment with multiple pouches, the pouches being open at the top of the pouches;
 FIG. 16 is a cross-sectional view thereof taken from line 16-16 in FIG. 15 from the front perspective view;
 FIG. 17 is a rear perspective view thereof that illustrates the back of the garment lifted in order to show the pouch on the inside on the front of the garment; and,
 FIG. 18 is an additional rear perspective view thereof that illustrates the back of the garment lifted in order to show the pouch on the inside on the front of the garment.
 Any broken lines, including small and large dashed lines, showing portions of the design are for illustrative purposes only and form no part of the claimed design. The dot-dash broken lines show the bounds of the claim and form no part of the claimed design.
